FURNITURE CONSTRUCTION

Bertis F. Hamilton, Columbus, Ind., assignor to
 Hamilton Manufacturing Corporation, Columbus, Ind., a corporation of Indiana

Original application August 6, 1945, Serial No.
 609,121. Divided and this application June 22,
 1950, Serial No. 169,585

3 Claims. (Cl. 155—194)

1

This application is a division of my prior application Serial No. 609,121, filed August 6, 1945, now abandoned. The invention concerned relates to a stool or similar article of furniture provided with vertically extending supporting legs. More particularly, the invention relates to a brace structure located intermediate the vertical extent of the legs and serving to interconnect them and to strengthen and stiffen the support which they provide.

It has heretofore been proposed to interconnect the legs of a stool or similar article by encircling them with and securing them to a ring-like brace. To facilitate application of such brace to the legs, it has been common to make it of non-continuous form, or even to make it in sections; and the necessity of interconnecting the ends of the brace or of adjacent brace-sections to provide the desired rigidity and pleasing appearance has presented a problem.

It is an object of the present invention to produce an improved brace structure for interconnecting the legs of a stool or similar article of furniture. Another object of the invention is to produce a brace structure especially applicable to sheet-metal legs of arcuate cross-section. Still another object of the invention is to employ an improved arrangement for joining the overlapping ends of a brace structure which encircles and is secured to the legs of a stool or the like.

In carrying out the invention, the brace is formed to encircle the legs it is to interconnect and to have overlapping ends meeting at one of such legs. The inner one of such overlapping ends is formed to seat against the exterior surface of the associated leg, while the outer one is shaped to fit against the outer surface of the inner one. The inner one of the overlapping ends is provided with an opening which receives an inwardly offset portion on the outer overlapping end; and such offset portion and the associated leg are provided with aligned openings for the reception of a clamp bolt.

The accompanying drawing illustrates the invention: Fig. 1 is a side elevation of a step stool in which the invention has been embodied; Fig. 2 is a horizontal section on the line 2—2 of Fig. 1; and Fig. 3 is a fragmental horizontal section on an enlarged scale, on the line 3—3 of Fig. 1.

The particular stool shown in the drawing comprises a seat 10 to which there are attached four seat-supporting legs 11. Below the seat, the front and rear legs of each side of the stool are interconnected by a strut 12; and below the

2

strut 12, all four legs are interconnected by a brace which encircles them, and which in the stool structure illustrated, consists of separate front and rear sections 13 and 14, the front section 13 extending between the two front legs and the rear section 14 being generally U-shaped and extending continuously from one front leg to the adjacent rear leg, between the adjacent rear legs, and thence to the other front leg. Links 15 pivotally connected with the brace 12 and with the sides of the rear-brace 14 interconnect the stool with a ladder 16 and provide for movement of the ladder from the extended full-line position through the dotted-line position to the retracted chain-line position shown in Fig. 1. The particular stool shown and described is employed herein merely for purposes of illustration, as my invention is not concerned with any particular type of stool but rather with the manner in which overlapping ends of the brace 13—14 are secured together and to the legs 11.

In the specific structure shown in the drawing, the brace which interconnects the four legs is, as previously noted, formed of two sections 13 and 14. The ends of the front section 13 meet the ends of the rear section 14 in overlapping relationship at the two front legs of the stool. As indicated in Fig. 3, each end of the brace-section 14 engages the outer face of the adjacent leg 11 and is overlapped exteriorly by the adjacent end of the front brace-section 13. The outer of the overlapping brace ends and the adjacent leg 11 are provided with aligned openings for the reception of a clamp bolt 20. The inner one of the overlapping ends is likewise provided with an opening, co-axial with the bolt 20, but such opening is considerably larger than the bolt and receives an inwardly projecting boss 21 formed on the outer one of the overlapping brace-ends.

In the preferred form of construction, the legs 11 and the brace 13—14 are formed of sheet-metal. Desirably, in the plane of the brace 13—14 the legs are of the generally semi-circular section indicated in Fig. 3. To increase the strength and rigidity of the brace, as well as to enhance its appearance, its sections may be formed to have an outwardly convex arcuate cross-section. The inner of the overlapping brace-ends is desirably shaped to provide a seat 14' for the leg 11 which it engages, and the outer of the overlapping brace-ends is shaped to fit against the exterior surface of the inner brace-end. The boss 21 is conveniently formed by inwardly off-setting the metal of the outer over-

lapping brace-end, and preferably has a diameter great enough to permit it to receive the head of the bolt 20.

Where the brace crosses legs other than those which brace-ends overlap, it is desirably shaped, as by a slight outwardly offsetting, to provide seats 24 (Fig. 2) which receive such legs and to which the received legs are secured by bolts 25.

In the step-stool shown in the drawing, the front brace-section 13, in addition to cooperating with the rear section 14 to provide a ring-like structure which encircles and interconnects the legs, also provides a support for the ladder 16 in both extended and retracted positions of such ladder. To prevent interference of the front brace section with the ladder, its mid-portion is offset inwardly of the stool; and to adapt it for its function in supporting the ladder, it is formed with channel-like seats 26 adapted to receive horizontally extending portions of the ladder. Where the stool or other article embodying the invention of this application includes no such ladder as is shown in the drawing, the peculiar characteristics of the front brace-section just noted may be omitted. The number of sections constituting the brace may vary; but I prefer to form it in two sections, as its manufacture is thereby facilitated.

The inwardly concave cross-sectional shape of the brace insures that as the clamp bolts 20 and 25 are tightened the upper and lower edges of each leg-receiving seat in the brace will be drawn firmly into contact with the leg. As a result of this contact, the brace opposes any tendency of any leg to rotate about the axis of its associated clamp-bolt 20 or 25, thus contributing to the strength and rigidity of the support which the legs provide. The interconnection which each boss 21 provides between overlapping brace-ends relieves the associated clamp bolt of shearing stresses.

I claim as my invention:

1. In an article of furniture, an upper, gen-

erally horizontal load-sustaining member, legs secured to said member in spaced relation and extending downwardly therefrom, a brace interconnecting said legs at an elevation intermediate their vertical extent, said brace having overlapping end portions one of which lies against one of said legs and is provided thereat with an opening, the other of said overlapping end portions having a boss received and fitting such opening to locate the overlapping ends in relatively fixed position, said boss being provided within its limits with a second opening, the leg being provided with an opening aligned with said second opening, and a bolt extending through said openings for clamping the overlapping portions and leg together, the first mentioned of said overlapping end portions having means which engage the leg at points spaced above and below the boss and prevent said boss from engaging the leg when said bolt is tightened.

2. The invention set forth in claim 1 with the addition that said brace lies exteriorly of said legs.

3. The invention set forth in claim 1 with the addition that said brace is formed of sheet metal having an inwardly concave arcuate cross-sectional shape, the edges of said brace constituting the means which engage the leg and hold the boss from contact therewith.
